UNITED STATES PATENT OFFICE

GUSTAV A. VASEL, OF PHILADELPHIA, PENNSYLVANIA, ASSIGNOR TO WILLIAM WHARTON, JR. & COMPANY, INCORPORATED, OF EASTON, PENNSYLVANIA, A CORPORATION OF PENNSYLVANIA

MEANS FOR WIPI NG GRINDING ROLLS

Application filed February 14, 1930. Serial No. 428,531.

The object of the invention is to enhance the efficiency and to provide economical operation of color grinding machines of the type embodying co-acting grinding rolls; and the nature of the invention consists in the provision of means for trapping and directing back to the grinding faces, material thrown therefrom under the action of centrifugal force.

One embodiment of the invention is illustrated in the accompanying drawings forming a part hereof, wherein

Figure 1 is a fragmentary plan view of co-acting grinding rolls having trapping provisions embodying the invention.

Fig. 2 is an end view.

Fig. 3 is a section on line 3—3 of Fig. 2.

Fig. 4 is a detail of one of the end plates.

In the drawings, the numerals 1 and 2 indicate, respectively, the low and intermediate speed rolls of equal length as to grinding area. As usual the mass or material to be ground is delivered into the bight of said rolls through the intervention of hopper elements or end plates 3 having coincident arch portions 4 overlying the trunnions of the rolls and defined by stems 5. The rolls, also as usual, rotate, respectively, in a clockwise and counter-clockwise direction. In practice and due to the centrifugal force generated by the rolls, there is a tendency for the material in the end zones to escape from the rolls by leakage endwise thereof. In order to obviate this and in the practice of my invention, the end or hopper plates have abutting or wiping contact with the end faces of the rolls and are provided on the roll side and in the plane of the grinding faces with open slots or grooves 6, one for each roll,

whose office it is to trap leakage and direct the same back into the mass suspended in the bight of the rolls. Excellent results have been achieved in practice by using tapered grooves of the form more particularly shown in Fig. 4.

The invention is not concerned with the details of mounting the end plates which, obviously, may vary, it being sufficient to say they are adjustable to take up wear and maintain wiping contact.

Having described my invention, I claim:

1. The combination of co-acting grinding rolls, and hopper plates coating with the ends of such rolls for wiping contact therewith, the margins of the plates being formed with grooves opening through such margins and extending tangentially of the adjacent roll surface and above and below such surface and toward the bight of said rolls.

2. The combination with co-acting grinding rolls, and hopper plates having end wiping contact therewith, said plates being formed with grooves opening through the margins of such plates and extending toward the bight of the rolls, said grooves having a width to extend above and below the plane of movement of the roll surface substantially throughout the length of the groove.

3. A hopper element for grinding rolls, comprising a flat plate having arch portions adapted to overlie the roll trunnions so that the plate will bear against the ends of a set of rolls, the plate having grooves above the arch portions and of a width to extend above and below the plane of movement of the roll surfaces, said grooves extending toward the bight of the rolls and effective to trap leakage and direct the same back into the mass suspended into the bight of the rolls.

In testimony whereof I affix my signature.

GUSTAV A. VASEL.
